(57) **CLAIM**

We claim the ornamental design for a robotic device, as shown and described.

DESCRIPTION

FIG. 1 is a front perspective view of a robotic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom rear perspective view thereof;

FIG. 9 is a front perspective view with accessory features in broken lines;

FIG. 10 is a rear perspective view of FIG. 9;

FIG. 11 is a front perspective view with accessory features in broken lines;

FIG. 12 is a rear perspective view of FIG. 11;

FIG. 13 is a front perspective view with accessory features in broken lines; and,

FIG. 14 is a rear perspective view of FIG. 13.

The broken lines in the figures showing portions of the robotic device form no part of the claimed design. The broken lines showing the accessory features in FIGS. 9 to 14 are for environmental purposes only and form no part of the claimed design.
